United States Patent Office

Des. 211,336
Patented June 11, 1968

211,336

SETTEE

Louis Kettman, Rte. 1, Waterloo, Iowa 50701
Filed Sept. 30, 1966, Ser. No. 4,117

Term of patent 14 years

(Cl. D15—11)

FIG. 3.

FIG. 3 is a back perspective view thereof.

I claim:

The ornamental design for a settee, as shown.
